UNITED STATES PATENT OFFICE.

PAULINA OWSIAK, OF FALL RIVER, MASSACHUSETTS.

WASHBOILER.

1,234,076.

Specification of Letters Patent. Patented July 17, 1917.

Application filed April 30, 1917. Serial No. 165,596.

To all whom it may concern:

Be it known that I, PAULINA OWSIAK, a subject of the Emperor of Austria, residing at Fall River, in the county of Bristol and 5 State of Massachusetts, have invented certain new and useful Improvements in Wash-boilers, of which the following is a specification.

This invention relates to clothes boilers 10 and has special reference to a clothes boiler provided with means for making the circulation of the detergent fluid and steam through the clothes being washed.

One important object of the invention is 15 to improve the general construction of devices of this character.

A second important object of the invention is to provide an improved form of screen and distributing devices for use in 20 connection with clothes boilers.

With the above and other objects in view, as will be hereinafter apparent the invention consists in general of certain novel details of construction and combinations of 25 parts hereinafter fully described, illustrated in the accompanying drawing, and specifically claimed.

In the accompanying drawing, like characters of reference indicate like parts in the 30 several views, and:—

Figure 1 is a plan view of a clothes boiler constructed in accordance with this invention.

Fig. 2 is a bottom plan view of the distributing screen.

Fig. 3 is a section on the line 3—3 of Fig. 2.

Fig. 4 is a section on the line 4—4 of Fig. 2.

Fig. 5 is a detail perspective view of the intersection of certain supporting ribs having baffles connected thereto.

In the form of the invention herein illustrated there is provided a clothes boiler having the side wall 10 and bottom 11, the boiler being of the usual elongated form. Spaced above the bottom of this boiler is a removable plate 12 which is held parallel to the

bottom by means of partition strips 13 intersecting each other at right angles and extending along the major and minor axes of the boiler. These strips have extending at right angles thereto crenelated baffle strips 14, the baffle strips at one end of each of the strips 13 being directed oppositely to those at the other end as can be clearly seen from an inspection of Fig. 2. Moreover the crenelations in the strips 14 are arranged to lie in spaced relation to both the plate 12 and bottom 11 as seen in Figs. 60 3 and 4. Between the strips 14 the strips 13 are provided with circulation notches 15 which open downwardly and thus permit fluid to flow in any direction along the bottom of the boiler. The plate 12 is provided with a multiplicity of perforations 16 and has at each end a lifting handle 17.

Now when the boiler is placed over a fire it will be seen that the steam bubbles, formed on the bottom, will pass upward through 70 the water and striking the crenelated strips will be scattered all over the plate 12 to pass up through the openings 16 and thus the rising steam and streams of water passing up and down will be distributed throughout 75 the entire mass of clothes held on the plate 12, whereby all of the clothes will be exposed thoroughly to the detergent.

There has thus been provided a simple and efficient device of the kind described and 80 for the purpose specified.

It is obvious that many minor changes may be made in the form and construction of the invention without departing from the material principles thereof. It is not 85 therefore desired to confine the invention to the exact form herein shown and described but it is wished to include all such forms as properly come within the scope claimed.

Having thus described the invention, what 90 is claimed as new, is:—

The combination with a wash boiler; of a removable plate parallel to the bottom of the boiler and provided with a multiplicity of perforations, partition strips beneath said 95 plate and extending centrally thereof at

right angles to each other, said strips being provided with notches in their lower edges and forming supports for the perforated plate, and spaced crenelated baffle strips extending from the partition strips at right angles thereto, said baffle strips extending in opposite directions from the opposite ends of the partition strips and spaced from

the bottom of the boiler and the perforated plate.

In testimony whereof I affix my signature.

PAULINA OWSIAK.
